BORE-SIGHTER FOR FIREARMS

Claus O. Huckenbeck, Sherman Oaks, Calif., assignor to
Bausch & Lomb, Incorporated, Rochester, N.Y.

Filed Jan. 2, 1975, Ser. No. 538,087

Term of patent 14 years

Int. Cl. D22—05

U.S. Cl. D22—8

FIG.1

FIG.3

FIG.2

FIG.4

FIG. 5

Des. 241,245

Page 2 of 2

FIG. 6

FIG. 7

FIG. 1 is a right-side elevation of the bore-sighter for firearms;

FIG. 2 is a left-side elevation of the device;

FIG. 3 is a rear end view of the device, the upper circular surface being a translucent disk;

FIG. 4 is a front end view of the device;

FIG. 5 is a top view of the device;

FIG. 6 is a bottom view of the device; and

FIG. 7 is a perspective view showing the front, top and right-side surfaces of the device.

I claim:

The ornamental design for a bore-sighter for firearms, substantially as shown and described.
